UNITED STATES PATENT OFFICE.

WILLIAM H. LUTZ, OF PHILADELPHIA, PENNSYLVANIA.

QUILTING-MACHINE.

1,313,308.

Specification of Letters Patent. Patented Aug. 19, 1919.

Application filed July 25, 1916. Serial No. 111,101.

To all whom it may concern:

Be it known that I, WILLIAM H. LUTZ, a citizen of the United States, residing in the city and county of Philadelphia, State of Pennsylvania, have invented a new and useful Quilting-Machine, of which the following is a specification.

The present invention relates to a machine for sewing together, generally in a fancy pattern the parts of a quilt, comfort or covering of a like nature and has for an object to provide a supporting carriage for the quilt or like article, which is freely movable laterally in any direction and is under the control of a guide in the form of a pattern whereby a line of sewing may be worked on the quilt according to a predetermined configuration of any fanciful nature or otherwise. In the manufacture of quilts by machinery and according to given pattern designs it is necessary, in some instances, in order to properly and more expeditiously work the design upon the quilt, to provide two sewing heads instead of a single sewing head and another object of the invention is to provide means whereby the same machine may be readily converted from a single head single pattern machine to a double head double pattern machine.

A further object is to provide a mechanism whereby the design of the pattern may be reproduced a number of times upon the same quilt and in consequence the pattern structure is greatly simplified.

It also has for an object to provide a mechanism which may be adjusted for substantially any width of quilt made under ordinary standards and which mechanism is vertically adjustable to insure the proper placing of the quilt in alinement with the sewing head or heads and shuttle table or tables.

It has for a still further object to provide a fixed or stationary support for the sewing mechanism and its adjuncts whereby excessive tension of the quilt in its movement will not cause the sewing head support to be distorted and produce an irregular sewing of the quilt as takes place where the machine is constructed with the sewing head machine mounted on a movable frame.

It further consists of other novel features of construction, all as will be hereinafter fully set forth.

For the purpose of illustrating my invention, I have shown in the accompanying

drawings a preferred embodiment which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a plan of a quilting machine embodying my invention.

Fig. 2 represents an end elevation of the same.

Fig. 3 represents a plan of one of the quilt clamps and its adjuncts.

Fig. 4 represents a side elevation, partly in section of the same.

Fig. 5 represents a vertical longitudinal section of the quilting machine.

Fig. 6 represents a vertical section of one of the adjustable supports for the quilt conveyor mechanism.

Fig. 7 represents a section on line $\alpha-\alpha$ of Fig. 2.

Fig. 8 represents a section on line $y-y$ of Fig. 2.

Fig. 9 represents a side elevation of one of the sewing heads showing in section the support and driving mechanism therefor.

Fig. 10 represents a similar view of the work table and its adjuncts.

Fig. 11 represents a section of any one of the head or shuttle clutch control devices.

Fig. 12 represents a plan of a single head pattern and its adjuncts.

Fig. 13 represents a section on line 13—13 of Fig. 12. Fig. 14 represents a modified form of pattern.

Similar numerals of reference indicate corresponding parts in the figures.

Referring to the drawings:

1 designates a pair of standards fixedly secured to the floor or other suitable stationary base, and provided respectively with pairs of tubular heads 2, whereby the tubular members 3 and 4 are supported one above the other in parallel relation. These two members 3 and 4 therefore extend from one standard to the other and form respectively fixed supports for the sewing machine tables or bed plates 5 and the sewing heads 6. Since the precise construction of these tables, the shuttle mechanism 7 and the sewing heads 6 is substantially immaterial and

may be of any well known form suitable for the purpose, a detailed description of their several parts is thought unnecessary. It will, however, be noted that both the tables 5 and heads 6 are mounted on their respective supports in such a manner as to provide for adjustment longitudinally of the tubular members 3 and 4, while the heads 6 are in addition capable of independent rotary adjustment and therefore this construction will be described since it forms a material embodiment of the complete unitary structure comprising my invention.

8 designates the respective cross slides for the sewing heads and work tables, the same having rearwardly extending lugs 9 of suitable contour to conform to the shape of the tube members 3 and 4 and being fixed thereto by studs 10 or like fastening devices. The cross slides 8 are provided as usual with suitable ways or guide surfaces 11 to receive and support in sliding relation the guide ways 12 of the tables 5 and the heads 6, it being noted that a liner 13 or strip of metal is inserted between one guide way 11 of each cross slide and its component part so that tightening of the set stud 14 fixes the part in adjusted position. By reference to Fig. 2, it will be seen that the cross slides 8 are of sufficient length to permit a relatively wide range of adjustment for the tables 5 and heads 6 transversely of the machine, it being understood that the heads are located opposite the tables in paired relation, that is to say, each head operates in conjunction with a table as will be readily understood. The cross slides 8 in each instance are also preferably provided with suitable dowel pins 15 adapted to seat in openings formed in the members 3 and 4 in order to reduce the shearing strain on the studs 10 and furthermore insure proper alignment.

In the preferred embodiment of the invention there are three sets of tables and heads as shown in Fig. 2, the middle or single set being used for single head work when a single pattern is employed and the outer sets for double head work when a double pattern is used. In this latter type, the two heads operate simultaneously each reproducing the design or pattern traced by the other. For this purpose, I preferably provide a pivoted construction for the respective heads 6 so that the one or ones not in use may be swung to an inoperative position as indicated in dotted lines—Fig. 2. Each head in the present instance is fed from a thread cap 16 as will be apparent.

17 designates a frame (Figs. 7 and 8) fixed to the tube 3 by studs 18 for the purpose of forming a support and bearing for certain adjuncts of the driven and control mechanism for operating the moving parts. Journaled in this frame 17 is a spindle 19 carrying thereon a pulley 20, which receives

power from any suitable source and transmits it to a worm 21 and a bevel gear 22, the former being keyed or otherwise fixed to the spindle 19, and the latter secured by a set screw 23 or equivalent means. The bevel gear 22 is normally in mesh with a similar gear 24 (see Fig. 2) fixed to the shaft 26, the latter being suitably journaled in bearings 27 and extending from the central portion of the machine to one side thereof where it carries a second bevel gear 28 which serves to transmit motion to the heads 6 and shuttle mechanism 7. This action takes place through the medium of bevel gears 29, 30 and 31, all of which are fixed to the stub shaft 32 and are respectively in mesh with the bevel gears 28 and the two gears 33. It will of course be understood that suitable brackets 34 are provided to support the shaft 32 from a fixed portion of the frame. One of the gears 33 is fixed to a spindle 35, located adjacent and parallel to the tube 3 and having the gear 36 loosely sleeved thereon to transmit motion to a gear 37 for actuating the shuttle mechanism 7 when the sleeve is clutched as will be later explained. The other gear 33 is fixed in like manner to a shaft 38 which transmits motion to the sewing head mechanism by way of the sleeved gear 39 meshing with the gear 40 of the head driving means.

41 designates a plurality of clutch parts for controlling the actuation of the respective sewing heads or shuttle mechanism, each clutch part being preferably keyed for sliding movement to its proper shaft. Thus each of the shafts 35 and 38 carries, in the present instance, three clutch parts, each of which may be independently adjusted along the shaft and fixed in operative position by tightening its set screw 42.

The sleeved extension of the respective gears 36 and 39 carries a complementary part 43 of the clutch so that when the part 41 is moved into engagement therewith, then motion of the shaft is transmitted to the gear to be driven. 44 designates a vertically disposed spindle mounted for sliding movement in the frame 17 and having a worm gear 45 keyed thereto and normally meshing with the worm 21 of the driven shaft 19. In this construction, the spindle 44 is provided with a relatively long key-way so that it is still in driving connection with the gear 45 irrespective of its position, this being an important detail as the controlling pinion 46 for engaging the rack requires to be moved up or down according to the position of the pattern and since it is fixed to the spindle 44 both must move together. The pattern rack 47 is shown in section in Fig. 8 with the pinion 46 operatively engaging it. The shifting movement of the spindle 44, is manually controlled by a lever 48 pivoted at 49 to the frame 17, and fixed at 50 to a

collar 51 secured to the spindle 44. 52 designates a link to which the lever 48 is connected and adjustment provided by means of a series of apertures 53 and a pin 54. This 5 link 52 is secured to an arm 55 fixed to a rock-shaft 56 which is suitably journaled at 57 and 58 and extends to a convenient point, where it terminates in a hand-wheel 59, by which the parts are shifted as desired. In 10 connection with the above described movement of the spindle 44, it may be stated that this shaft is only shifted from one position to another when the pattern is changed by superposing one on another.

15 Having now described those parts of the machine having a bearing more particularly upon the sewing head parts, I will now take up in detail the description of those parts which have to do with supporting, guiding 20 and carrying the quilt.

The quilt carrier mechanism and the movable adjuncts thereof, in the present instance, are supported upon a carriage 60, which is preferably of sufficient length to 25 support a pair of quilts, whereby it is possible for the machine to be working upon one quilt, while another one is being positioned on the conveying mechanism ready to be moved into the machine as soon as the work 30 on the first quilt has been completed. In this type of machine where the quilts are automatically fed into the machine, the overhang or extension portion of the carriage 60 is supported for movement in any lateral 35 direction by the universally jointed casters 61, while the body part of the carriage is provided with two sets of wheels 62 and 64. Preferably one of these sets of wheels is provided with a groove 63 in order to straddle 40 a suitable rail 66 mounted upon an auxiliary carriage 65 so that while the carriage 60 may move transversely of and relative to the carriage 65, a longitudinal movement thereof will be transmitted to the auxiliary carriage 45 and cause it also to move in the required manner. The wheels 64 are adapted to run upon a suitable flat rail 67 as will be understood. The auxiliary carriage 65 in order to move as indicated, is supported 50 upon wheels 68, mounted upon rails 69 on the floor or other support, and arranged longitudinally of the machine, so that the quilt conveying mechanism not only has a movement in a transverse direction, but also in 55 a longitudinal direction, since the carriage 60 may move either with the auxiliary carriage 65 or relative thereto, as occasion demands. One of the rails 69 is preferably flanged to prevent improper movement of 60 the carriage 65.

In view of the fact that the parts carried by the carriage 60 are more or less heavy, especially the pattern rack, it is essential that the carriage supporting face be suitably 65 braced to prevent warping, and for that

purpose I employ a plurality of channel bars 70, spaced at suitable intervals throughout the length of the carriage, as will be seen by reference to Fig. 5, while cross stringers 71 are provided for the auxiliary carriage 70 65 as will be apparent.

72 designates a plurality of tubular housings arranged in pairs and suitably secured, at desired intervals to the carriage 60, by means of bolts 73 or the like. Each of these 75 housings serves as a seat for a pedestal member 74 having a bed 75 movably and adjustably mounted thereon, the said adjustment, in the present instance, being accomplished by means of a threaded bolt 76 passing 80 through a leader nut 77 fixed to the bed by set screws 78, while the said bolt is fixed to the pedestal by collar members 79 and terminates in a square head 80 adapted to receive a socket wrench or the like for operating purposes. The bed 75 is provided with a guide way 81, preferably of under-cut form to interfit with the guideway 82 of a supplemental bed 83, which is also provided with an upper guide way 84 to receive certain adjuncts now to be described.

85 designates an upright, fixedly carried adjacent one end of each of the beds 83, and serving as a bearing support for the spindles 86 of the guide rolls 87. The ends of 95 the spindles 86 are journaled in standards 88, each of which has sliding engagement with the supplemental bed guide ways 84 so that the standards may be moved toward or away from each other in order to conform to 100 the width of the particular quilt. To provide for the required movement of the said standards 88, I employ the rods 89 journaled at either end of the respective standards 88 and provided with right and left hand screw 105 threads 90 and 91, which coact with threaded bosses 92 of the said standards 88. A hand crank 93 is attached to each end of the rods 89 so that the parts may be adjusted from either side of the machine.

In order to affect independant vertical adjustment of the guide rolls 87, the pedestal members 74 each seat upon a stud 94 threaded into the housing 72 and located in a suitable opening 95 of the carrier platform 60. 115 A locking nut 96 is provided for each stud for the purpose of fixing the parts in adjusted position.

Each of the standards 88 carries a stub shaft 97 mounted in suitable bearings for 120 rotary movement, and having a sprocket 99 thereon to support and feed a conveyer chain 100. Similar sprockets 99 are mounted in pairs on the respective guide roll spindles 86 to rotate therewith for the purpose 125 of conveying and supporting the chains 100 in their line of travel along the upper portion of the machine.

By reference to Fig. 2 of the drawings, it will be seen that there are two of these 130

chains 100, one at each side of the machine, supported upon the sprockets 99 and extending longitudinally of the machine, there being, of course, as many pairs of standards 5 88 as necessary to support the aforesaid chains. At suitable intervals throughout the length of the conveyer chains 100 there are clamping devices arranged in opposed relation for engaging or gripping the side 10 edges of the quilt and holding it properly extended for the sewing operations. In the present instance, each of these clamping devices is fixed by screws 101, or the like, to lugs 102 forming a part of one link of the 15 chain and the base member 103 of the clamp comprises a jaw 104 preferably formed by a transverse groove 105 and also having a pair of projecting wings 106, between which the movable jaw 107 is pivoted, as shown 20 at 108. The jaw 107 is normally held closed by a spring 109 mounted on the pivot 108 and having its ends fulcrumed upon the ears 110 of the wings 106. Each base member 103 carries a roller 111 rotatably mounted 25 on a pin 112 which in the present construction, is clamped between a split portion of the member 103 by a screw 113. The jaw members 107 are each, also, provided with a roller 114 carried by a pin 115 and 30 laterally extending to bring the said rollers into a suitable position for engagement with a track mechanism now to be described.

In taking up the description of the track portion of the conveyer mechanism attention is directed to the fact that in the preferred automatic type of machine there are 35 two distinct sections, one being above the auxiliary carriage 65 and the other above that part of the carriage 60 which projects 40 beyond the end of the auxiliary carriage 65. The former section of the machine is of sufficient size to accommodate a complete quilt during the stitching operation, while the latter section is of similar dimensions and 45 utilized for the purpose of positioning the quilt correctly on the conveyer before it is delivered to the operating part. Thus it will be seen that the quilts may be handled expeditiously, one being placed in position, 50 while a second is being stitched and one operator can therefore readily take care of several machines.

116 designates a quilt supporting frame 55 formed of slat construction which is sustained by means of rods 117 having sliding or telescope engagement with hollow posts 118 mounted on the carriage 60, the said rods being fixed in adjusted position by set screws 119, as will be apparent. The side 60 portions of the operating section of the machine are fitted with side bars 120 located in the path of movement of the conveyer chains and having on the lower face thereof a groove or guide-way 121 to receive the rollers 111 and on the upper face a track 65 122

which is yieldingly mounted by means of strip springs 123. These latter are preferably of corrugated form and normally hold the plate 122 above the path of movement of the lower side of the rollers 114 70 so that when the latter contact with the plate 122 the springs 123 will be placed under compression and reinforce the action of the jaw springs 109 to such an extent as to prevent the quilt from being pulled out or 75 detached from the said clamping jaws. A bar 124 is secured to the standards 88 at each side of the machine, in order to suitably support the aforesaid side bars 120.

125 designates a cam track (Fig. 5) secured to the standards 88 at the ejecting end of the machine and positioned in the path of movement of the conveyer chains 100 for the purpose of engaging the outer portion 80 of the rolls 114, and thus automatically 85 cause the jaws to be released as the quilt leaves the machine.

126 designates a rack pattern suitably secured to the carriage 60 and adapted to be engaged by the pinion 46 when the latter 90 is lowered for the purpose of being guided by the single pattern. In some instances, it is desirable to employ a second pattern, that is one designed to simultaneously guide and control two sewing heads so that the 95 pattern is reproduced in duplicate upon the quilt. 127 designates such a pattern rack mounted upon a base 128 and it is adapted to be removably supported above the single pattern rack as shown in Fig. 2. 100

By reference to Figs. 11 and 12, a modified form of pattern rack will be seen, wherein a central partially rotatable pattern table 129 is employed in conjunction with the single head pattern. Thus the base 105 128 is recessed in circular form to receive the table 129 and the latter carries a suitable pinion meshing with the worm 130. The spindle 131 of the worm extends to a convenient point where it terminates in an 110 operating crank 132 as will be understood. Preferably the table 129 may only be turned through an angle of sixty degrees as is indicated by lines A and B and to this end the stops 133 are employed which are engaged 115 by the pins 134 carried by the table. Thus in Fig. 12, after the center pattern has been worked in its position as indicated by line A, it may be turned to position line B and repeated in this position. In Fig. 14, I have 120 shown a means whereby the number of sewing lines on the quilt may be varied at will by a simple rearrangement of the pattern rack. 135 designates a removable pattern section shown by way of example as connecting the outer and inner lines of the rack pattern so that the outer line of sewing is continuously with the inner line. In case the outer lines of sewing are desired to be 125 separate from the inner lines the section 135 130

may be removed and another section of suitable shape substituted to properly bridge the gap between the parts of the rack pattern. The conveyer mechanism is preferably adapted to be driven at will from a belt 180 indicated by dotted lines on Fig. 1.

In the operation of the machine, the quilt or other article to be stitched is first placed upon the table 116 with its side edges in parallel relation to the conveyer chains 100. The operator next adjusts the clamping devices 104 and 107 so that they grip the quilt along the edges and hold the same fast at suitable intervals and in stretched position between the chains. This position is of course determined by operating the handle cranks 93 to move the standards 88 toward or away from each other as the case may be. The proper rack pattern having been placed in position, which, in the present instance, we will assume is the pattern 127, the conveyer chains are simultaneously operated to move the article into position at the sewing section of the machine. In this position the rollers 114 have ridden upon the spring pressed rails 122, so that the clamping jaws are firmly held against any tendency of the quilt to pull free and the machine is then ready to begin the automatic stitching operation. With the power connected, the pulley 20 is driven to cause rotation of the pinion 46, which has of course, been moved into engagement with the rack pattern 127, so that its rotation causes the pattern to move thus shifting the carriage 60 in one direction or the other or causing the table 65 to move at right angles to this motion in either direction. There is therefore substantially a universal movement of the quilt supporting devices, their direction of movement corresponding to the contour of the pattern while the double sewing heads are reciprocating and each sewing a portion of the quilt. The pinion 46 of course traverses the full length of the rack pattern and when it has returned to its initial position, the quilt has been completely sewed and is ready for removal.

During the sewing operation a second article has been placed upon the table 116 and fixed to the conveyer chain, so that when the completed quilt is fed out of the machine, the uncompleted quilt automatically takes its place as the quilt is delivered from the end of the machine, the rollers 114 of the clamping jaws run into the cam tracks 125 and are thereby automatically opened to release the quilt from the conveyer.

It will now be apparent that I have devised a novel and useful construction which embodies the features of advantage enumerated as desirable in the statement of the invention and the above description and while I have in the present instance shown and described the preferred embodiment

thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. In a machine of the character stated, a frame, a plurality of sewing heads and a plurality of tables mounted on said frame in juxtaposed relation, a pattern, a holder for an article to be stitched, means to support said holder for lateral movement in any direction with respect to said tables, and means coacting with said pattern to impart to said supporting means a movement following the line of contour of said pattern whereby said article is correspondingly moved and stitched in lines conforming to said pattern. 75

2. In a machine of the character stated, a frame, a plurality of sewing heads and a plurality of tables mounted on said frame in juxtaposed relation, a pattern, a holder for an article to be stitched, means to support said holder for lateral movement in any direction with respect to said tables, and means coacting with said pattern to impart to said supporting means a movement following the line of contour of said pattern whereby said article is correspondingly moved and stitched in lines conforming to said pattern. 90

3. In a machine of the character stated, a frame, a sewing head and a table mounted on said frame in juxtaposed relation, a pattern, a conveyer comprising a plurality of chains, means to vary the distance between said chains to substantially conform to the width of an article supported therebetween, clamping devices carried by each chain to hold said article, means to support said conveyer for lateral movement in any direction and means co-acting with said pattern to impart to said supporting means a movement corresponding to the line of contour of said pattern. 100

4. In a machine of the character stated, a pair of standards fixedly mounted and spaced apart, a pair of tubular members arranged in superposed relation between said standards, a plurality of sewing heads carried by the upper member, a corresponding number of tables carried by the lower member and arranged respectively in juxtaposed relation to said heads, a double pattern, a holder for an article to be stitched, means to support said holder for transverse movement in any direction with respect to said tables, and means coacting with said pattern to impart to said supporting means a movement following the line of contour of said pattern whereby said article is correspondingly moved between said heads and 115 120 125 130

said tables and sewed in lines conforming to said pattern.

5. In a machine of the character stated, a fixed frame, a sewing head and a table 5 mounted on said frame in juxtaposed relation, means to actuate said head, a conveyer for an article to be stitched, a truck mounted for movement longitudinally of said frame, a carriage supported by said truck 10 for movement transversely of said frame, a plurality of vertically adjustable standards mounted on said carriage to support said conveyer, a pattern fixed to said carriage and means on said frame coacting with said 15 pattern to cause movement of said carriage or both truck and carriage, according to the contour of said pattern, whereby said article is moved to cause said sewing head to stitch lines of sewing similar to the contour 20 of said pattern.

6. In a machine of the character stated, a fixed frame, a plurality of sewing heads and a corresponding number of tables mounted on said frame in juxtaposed relation with respect to each other, means to actuate said heads, a conveyer for an article to be stitched, a truck mounted for movement longitudinally of said frame, a carriage supported by said truck for movement 25 transversely of said frame, a plurality of vertically adjustable standards mounted on said carriage to support said conveyer, a pattern fixed to said carriage, and means on said frame coacting with said pattern to cause 30 movement of said carriage, or both truck and carriage, according to the contour of said pattern, whereby said article is moved to cause said sewing heads to stitch lines of 35 sewing similar to the contour of said pattern.

7. In a machine of the character stated, a fixed frame, a sewing head and a table mounted on said frame in juxtaposed relation, means to actuate said head, a holder 45 for an article to be stitched, a truck mounted for movement longitudinally of said frame, a carriage supported by said truck for movement transverse of said frame, a pattern fixed to said carriage, and means on 50 said frame coacting with said pattern to cause movement of said carriage, or both truck and carriage, according to the contour of said pattern, whereby said article is moved to cause said sewing head to stitch 55 a line of sewing similar to the contour of said pattern.

8. In a machine of the character stated, a fixed frame, a plurality of sewing heads and a corresponding number of tables 60 mounted on said frame in juxtaposed relation with respect to each other, means to actuate said heads, a holder for an article to be stitched, a truck mounted for movement longitudinally of said frame, a carriage supported by said truck for move- 65

ment transverse of said frame, a pattern fixed to said carriage, and means on said frame coacting with said pattern to cause movement of said carriage, or both truck and carriage according to the contour of 70 said pattern, whereby said article is moved to cause said sewing heads to stitch lines of sewing similar to the contour of said pattern.

9. In a machine of the character stated, 75 a fixed frame, a sewing head and a table mounted on said frame in juxtaposed relation, means to actuate said head, a holder for an article to be stitched, a truck mounted for movement relative to said frame, a carriage supported by said truck for movement relative to said truck, a rack fixed to said carriage and arranged to form a pattern, a pinion rotatably mounted on said frame and meshing with said rack and 80 means to drive said pinion to cause movement of said carriage or both truck and carriage, according to the contour of said rack, whereby said article is moved to cause said sewing head to stitch a line of sewing similar to the contour of said rack. 85

10. In a machine of the character stated, a fixed frame, a sewing head and a table mounted on said frame in juxtaposed relation, means to actuate said head, a conveyer 95 mechanism for an article to be stitched, clamping devices mounted on said conveyer for holding an article in operative relation to said head and table, an auxiliary table for supporting a second article adjacent 100 said conveyer in position to be attached to said conveyer, a pattern mounted to transmit movement to said conveyer, means carried by said frame for moving said pattern, and means supporting said pattern for universal movement in substantially a horizontal plane. 105

11. In a machine of the character stated, a fixed frame, a sewing head and a table mounted on said frame in juxtaposed relation, means to actuate said head, a conveyer 110 mechanism for an article to be stitched, a plurality of clamping devices carried by said conveyer for holding said article, means operable at a predetermined time to lock 115 said clamping devices, a pattern and means to move said conveyer mechanism in a line simulating the contour of said pattern, whereby said article is stitched with a line of sewing similar to said pattern outline. 120

12. In a machine of the character stated, a fixed frame, a sewing head and a table mounted on said frame in juxtaposed relation, means to actuate said head, a conveyer 125 mechanism for an article to be stitched, a plurality of clamping devices carried by said conveyer for holding said article, means operable at a predetermined time to lock said clamping devices, means to automatically release said clamping devices to de- 130

liver said article from said conveyer, a pattern, and means to move said conveyer mechanism in a line simulating the contour of said pattern, whereby said article is stitched with a line of sewing similar to said pattern outline.

13. In a machine of the character stated, a fixed frame, a sewing head and a table mounted on said frame in juxtaposed relation, means to actuate said head, a conveyer mechanism for an article to be stitched, a plurality of clamping devices carried by said conveyer for holding said article, means operable at a predetermined time to lock 10 said clamping devices, rolls positioned at suitable intervals transversely of said conveyer to guide said article, a pattern and means to move said conveyer mechanism in a line simulating the contour of said pattern, whereby said article is stitched with 15 a line of sewing similar to said pattern outline.

14. In a machine of the character stated, a frame, a plurality of sewing heads and a plurality of tables mounted on said frame 25 in juxtaposed relation, said tables being provided respectively with shuttle mechanism, independent means for controlling the actuation of the respective heads and shuttle mechanism, a holder for an article to be 30 stitched, means to support said holder for lateral movement in any direction, a pattern, and means carried by said supporting means for engaging said pattern and imparting a movement to said holder whereby 35 a line of stitching is produced following the contour of said pattern.

In witness whereof, I have hereunto signed my name.

WILLIAM H. LUTZ.

Witnesses:

ROBERT M. BARR,
H. M. BYRNE.
